TERMINAL ASSEMBLY

Frank A. Newcombe, Nutley, N. J., assignor to
Westinghouse Electric Corporation, East Pitts-
burgh, Pa., a corporation of Pennsylvania

Application April 10, 1944, Serial No. 530,437

6 Claims. (Cl. 173—324)

1

This invention relates to the manufacture of incandescent electric lamps, and more particularly to a terminal assembly adapted for lamps of the "sealed-beam" type and the method of manufacture.

The principal object of my invention, generally considered, is to provide an improved terminal assembly for lamps of the "Mazda sealed-beam" type, as well as facilitate the method of manufacture.

Another object of my invention is to improve on the construction of terminal assemblies, such as used for the "sealed-beam" lamps, by replacing the copper wire ring, previously used for uniting the terminal post and lead-in element to the glass-connecting nickel-iron or "Kovar" ferrule or skirt, which serves to make a sealing connection with the glass of the envelope, by a thin sheet-copper eyelet conforming with the surfaces of the parts to be connected, thereby not only economizing in the use of metal for connecting said parts, but avoiding shrinkage by making it unnecessary for the parts being connected to move an appreciable distance while the brazing operation is being performed.

A further object of my invention is to improve on the method of connecting the parts of the terminal assembly for "sealed-beam" lamps by substituting, for the slow hand assembly and large fuel consumption in the method formerly used, a quick rotary method whereby the parts are separately fed to a conveyor which quickly brazes them one by one by small amounts of electrical energy while enclosed in a protecting manifold.

Other objects and advantages of the invention, relating to the particular arrangement and construction of the various parts, will become apparent as the description proceeds.

In the drawing:

Figure 1 is a side elevational view of a "Mazda sealed-beam" lamp which may embody my invention.

Figure 2 is an enlarged elevational view of one of the terminal assemblies manufactured in accordance with my invention.

Figure 3 is an exploded view of the parts of said assembly before connecting.

Figure 4 is a plan of a conveyor which may be used for connecting the parts of the assembly.

Figure 5 is a vertical sectional view, with parts in elevation, on the line V—V of Figure 4, in the direction of the arrows.

Figure 6 is a vertical sectional view, with parts

2

in elevation, on the line VI—VI of Figure 4, in the direction of the arrows.

Figure 7 is a sectional view, with parts in elevation, on the line VII—VII of Figure 4, in the direction of the arrows.

In accordance with previous practice the parts making up a terminal assembly for a "Mazda sealed-beam" lamp or one of those of that general type, one embodiment of which is described in the Wright Patent No. 2,148,314, designated as No. 4030, consist of a steel post having a collar adjacent one end, a nickel-iron or "Kovar" ferrule or skirt, the main portion of which is substantially frusto-conical, the inner portion of which, however, is bent at an angle thereto, leaving a short frusto-conical neck portion, reentrant with respect to the main portion, apertured to receive the post up to its collar, and presenting a surface conforming with that of said collar. "Kovar" is a nickel-cobalt-iron alloy, more specifically defined in the Lempert et al. Patent No. 2,279,831. In a preferred embodiment both surfaces are frusto-conical or extend at an acute angle to the axis of the post.

A small ring of copper, made from 50 mil wire, was used as a brazing medium between the post and ferrule. In the actual brazing operation the ferrule was placed on a plate, the copper ring set on top of the ferrule, and the post inserted in the hole so that its shoulder rests on top of the copper ring. The entire unit was then heated. In order to effect a proper brazing connection, the post had to slip down from .04 to .05 inch. In actual practice, many of the posts fail to move the required distance, with the result that the assembly was unsatisfactory for use.

In accordance with my invention, and referring to the drawing in detail, I substitute an eyelet 11 cut from copper sheet desirably from about .003 to .006 inch thick and pressed to the hollow frusto-conical shape illustrated in Fig. 3, so that it conforms not only with the frusto-conical surface 12 on the collar 13 of the contact post and lead-in conductor 14, but also with the opposed surface 15 of the reentrant frusto-conical hollow apertured collar or hub portion 16 on the ferrule or skirt member 17, the body of which, as will be observed, is generally frusto-conical although having a slight longitudinal curvature.

These parts, illustrated as separate in Figure 3, are shown connected in Figure 2 forming a terminal assembly 18, three of which are used for the double filament sealed-beam lamp 19 illustrated in Figure 1, as will be understood.

By substituting the eyelet 11 for a ring of cop-

per more than about five times as heavy, not only is a corresponding saving effected in metal used, but the motion during brazing of the parts is reduced to a negligible amount, thereby insuring that imperfections occurring during the operation are substantially eliminated.

In accordance with a preferred method of uniting the parts of the assembly, I use a rotary head machine 20 which may be similar to the staking machine 38 illustrated in Figure 3 of the Makenny application, Serial No. 516,014, filed December 29, 1943, and owned by the assignee of the present application. This machine has a rotary conveyor 21 which indexes its assembly-receiving pockets, preferably moving from one position to the next every two seconds.

The pockets which receive the parts of the assembly for brazing them together, each comprises an insulative plate 22 fitting in a corresponding pocket or cavity 23 in the top of the conveyor 21 receiving an annular or modified hollow cylindrical electrode plate member 24, preferably formed of durable material such as a molybdenum alloy and desirably held in place by means of an annular insulative member 25. The portions 22 and 25 may, in turn be connected to the conveyor 21 by screws or the like 42.

In each aperture 26 through the conveyor 21, is a spring chuck 27 which has fingers 28 rotatably mounted on a pivot shaft 40 fixed to said conveyor, resiliently urged together by spring 42, and which grip the lower end of a terminal post 14, when inserted from the dotted line position to the full line position illustrated in Figure 5, thereby holding collar portion 12 thereof in firm engagement with an eyelet 11 previously applied to the collar portion 15 on a ferrule or skirt 17 resting on the electrode 24. The upper portion of the electrode 24 is desirably tapered to conform with the ferrule 17 so that when one of the latter is nested thereover, its lower edge is held above the insulative member 25.

The operation of the machine illustrated in Figures 4 to 7, inclusive, is desirably as follows:

At position 29, in Fig. 4, the ferrule or skirt members are placed one at a time each time the machine indexes, each with its lower edge portion centered by fitting over an electrode 24, as illustrated in Figure 5. At position 30, eyelets 11, or posts 14 each with an associated eyelet 11, are fitted, each to an already-positioned ferrule or skirt 17, as illustrated in the same figure. At position 31, post members 14, if not fed at position 30, are each moved down through registering apertures in a positioned eyelet and skirt assembly, so that the lower end portions are each gripped between fingers 28 to hold the parts in full line position, as illustrated in said Figure 5, if such did not occur at position 30.

The placing of the parts may be effected automatically or by hand. As an alternative, the skirt-eyelet-post elements may be nested, and then fed to the machine, automatically or by hand, at one position.

After position 31, the nested or assembled parts move with the conveyor 21 into manifold 32 where they are protected by reducing or inert gas fed thereto as through pipe 33.

In position 34 and while still in said manifold, a brazing plunger electrode 35, preferably formed of durable material such as a molybdenum alloy, reciprocable in head 36 and held in resilient relation thereto by spring 37, descends into engagement with the top of post 14, or preferably the collar 13 thereof, and a suitable amount of elec-

trical energy is passed between said plunger 35 and the supporting electrode 24, thereby softening or melting the eyelet 11 between the resiliently pressed parts of the contact assembly, so that it serves to braze the post 14 to the skirt portion 17. In order to avoid heating more than necessary of the post 14, the electrode 35 is desirably formed with a downwardly-opening pocket 48 allowing enough clearance, around the received upper portion 41 of the post 14, so that its lower surface 44 engages the upper surface of the collar 13 of the post 14.

The next few positions on the conveyor allow for cooling of the connected parts. In position 15 the brazed parts are withdrawn, by hand, or automatically as by means of a pair of fingers 39 gripping the upper end portion 41 of the post 14 and removing the complete terminal assembly from the machine, against the holding action of the spring-actuated fingers 28.

As an alternative, the brazing may be effected as heretofore described, but in the open rather than under a manifold, and the parts then quickly cooled, as by a jet of water, before removing the upper electrode 35 from engagement with the post 14. Such a method avoids the necessity for the hold-down fingers 28, as well as the protective atmosphere and its manifold 32 during brazing, because the parts are actually brazed together while being resiliently held in place by the upper electrode, and the time during which they are exposed to the atmosphere while hot is so short that no undesirable oxidation occurs.

From the foregoing disclosure it will be seen that I have not only provided for a more economical construction of the terminal assembly, but also for an improved method for effecting such assembly, and eliminated the necessity for one operator. By the method formerly used two operators were employed, one for assembling the parts and one for attending to the furnace, whereas in accordance with my invention one operator only is needed to attend the machine. By virtue of the special form of the electrodes only small parts of the associated posts and ferrules are directly heated by passage of the brazing current.

Although a preferred embodiment of my invention has been disclosed, it will be understood that modifications may be made within the spirit and scope of the appended claims.

I claim:

1. A terminal assembly for electrical devices comprising a contact prong and lead-in element formed as an elongated metal conductor with a collar adjacent one end, a generally frusto-conical hollow thin metal skirt member receiving said conductor in a central aperture, with its inner edge portion turned at an angle thereto and presenting a surface conforming with the adjacent surface of said collar, and a thin sheet-metal eyelet sandwiched between said surfaces and serving to hold the parts in assembled relationship.
2. A terminal assembly for electrical devices comprising a steel contact prong and lead-in element formed with a collar adjacent one end, a generally frusto-conical hollow thin nickel-cobalt-iron skirt member receiving the portion of said element remote from said collar in a central aperture, with its inner edge portion turned at an angle thereto and presenting a surface conforming with the adjacent surface of said collar, and a thin sheet-copper eyelet sandwiched between said surfaces and fused to hold the parts in assembled relationship.
3. A terminal assembly for electrical devices

comprising a contact prong and a lead-in element formed as an elongated metal conductor with a collar adjacent one end, that portion of said collar facing the remote end of said conductor being formed with a frusto-conical surface, a generally frusto-conical hollow thin-metal skirt member receiving the collar-remote end portion of said conductor in a central aperture, with its inner edge portion turned at an angle thereto to conform with the adjacent frusto-conical surface of said collar, and a thin sheet-copper eyelet sandwiched between said frusto-conical surfaces and serving to hold the parts in assembled relationship.

4. A terminal assembly for electrical devices comprising a contact prong and lead-in element formed as an elongated steel conductor with a collar adjacent one end, that portion of said collar facing the remote end of said conductor being formed with a frusto-conical surface, a generally frusto-conical hollow thin nickel-cobalt-iron skirt member receiving said collar-remote end portion in a central aperture, with its inner edge portion turned at an angle thereto and presenting a frusto-conical surface conforming with the adjacent surface of said collar, and a thin sheet-copper frusto-conical eyelet sandwiched between said surfaces and fused to hold the parts in assembled relationship.

5. A terminal assembly for electrical devices comprising a contact prong and lead-in element formed as an elongated metal conductor with a collar adjacent one end, a thin hollow metal skirt member through a central aperture in which said conductor passes, the inner edge portion of said skirt member being disposed at an angle thereto and having a surface conforming with the adjacent surface of said collar, and a sheet metal eyelet of material from about .003 to .006 inch thick sandwiched between said surfaces and serving to hold the parts in assembled relationship.

6. A terminal assembly for electrical devices comprising a steel contact prong and lead-in element formed with a collar adjacent one end, a thin hollow flaring skirt member formed of a nickel-cobalt-iron alloy and through a central aperture in which extends a portion of said element remote from said collar with its inner edge portion extending at an angle thereto, and having a surface conforming with the adjacent surface of said collar, and a sheet copper eyelet of material from about .003 to .006 inch thick sandwiched between said surfaces and fused to hold the parts in assembled relationship.
